VACUUM TUBE HOLDER

William G. Leichner, Fort Wayne, Ind., assignor
to Farnsworth Television and Radio Corpora-
tion, a corporation of Delaware

Application April 30, 1942, Serial No. 441,218

1 Claim. (Cl. 173—328)

This invention relates to holders for vacuum tubes and more particularly to such holders which are to be used under conditions involving an excessive degree of vibration.

Conventional tube holders usually consist of a flat base member to which there is attached a number of contact elements which are adapted to engage the prongs of a vacuum tube. However, in radio equipment or sound reproducing equipment which is to be used in motor vehicles or factory buildings where there is excessive vibration, it is necessary to provide a means for positively gripping or clamping the base of the tube whereby it may be held firmly in position and in contact with the spring contacts to which circuits may be connected.

The primary object of this invention is to provide a novel tube holder which is vibration proof. Another object of this invention is to provide a tube holder which is adapted to grip or clamp the base of the tube.

For a better understanding of the present invention, together with other and further objects thereof, reference is had to the following description taken in connection with the accompanying drawing and its scope will be pointed out in the appended claim.

Referring to the drawing:

Fig. 1 of the drawing is a plan view of a tube holder constructed in accordance with this invention;

Fig. 2 is a front view of the tube holder illustrated in Fig. 1, the tube holder being in its open or free position;

Fig. 3 illustrates the tube holder shown in Figs. 1 and 2 in its closed or clamping position;

Fig. 4 is a top view of a modification of this invention;

Fig. 5 is a front view of the holder shown in Fig. 4 from the direction indicated by arrows 5, 5;

Fig. 6 is a cross-section taken of line 6—6 in Fig. 4.

Fig. 1 of the drawing illustrates a tube holder constructed in accordance with this invention comprising a base member 1 to which there is attached contact springs 2 and cylindrical holding or clamping elements 3 and 4. Elements 3 and 4 are secured to base 1 by means of the brackets 5 and 6 and screws 7. The cylindrical elements 3 and 4 are so shaped or deformed that their composite diameter at the top is slightly less than the diameter at the bottom, the purpose of which will be obvious from subsequent description. Ring 8 surrounds the elements 3 and 4 and

is so dimensioned that it fits freely when in the position illustrated in Fig. 2, but the inner diameter of ring 8 is chosen to be somewhat less than the outer diameter of the holder at the point 9. 5 The cylindrical elements 3 and 4 are also spaced apart to a slight degree as shown in Figs. 1 and 2.

The vacuum tube base 10 which is shown in Figs. 2 and 3 is inserted so that its base is flush with the base 1 and its prongs are in full contact 10 with contact springs 2. Ring 8 may then be forced downwardly to the position illustrated in Fig. 3 to deflect the cylindrical elements 3 and 4 together as illustrated in Fig. 3, at which time tube base 10 is firmly gripped or clamped by elements 3 and 4. Ring 8 holds elements 3 and 4 in this position because of the effects of frictional contact with them.

The modification of the invention illustrated in Fig. 4 is similar to that shown in Figs. 1, 2 and 3, except that it consists of three cylindrical elements 12, 13 and 14 which are spaced apart to a slight degree and have a slightly smaller diameter at the top than at the bottom. The ring 15 is similar to ring 8 except that its interior 15 surface is cut to comprise three cam surfaces 18, 19 and 20. Ring 15 is dimensioned to have a loose fit with respect to cylindrical elements 12, 13 and 14 when it is positioned at the top of the holder, but the inner diameter of ring 15 is chosen to be somewhat less than the outside diameter of the holder at point 16, shown in Fig. 6. Each of the elements 12, 13 and 14 has a cut-out portion 22 which is bent at 23, shown in Figs. 5 and 6, to provide a stop for limiting the downward motion of ring 15 on the cylindrical elements 12, 13 and 14.

The vacuum tube may be inserted in this modification of the tube holder and firmly gripped or clamped by manually forcing ring 15 downwardly into the position shown in Fig. 5 and rotating it in a counterclockwise direction from the position shown in Fig. 4. When rotated approximately 45°, cam surfaces 18, 19 and 20 will so distort the cylindrical elements 12, 13 and 14 that they are forced against the base of the vacuum tube to thereby clamp it firmly.

While there has been described what is at present considered the preferred embodiment of the invention, it will be obvious to those skilled in the art that various changes and modifications may be made therein without departing from the invention, and it is, therefore, aimed in the appended claim to cover all such changes and modifications as fall within the true spirit and scope of the invention.

What I claim is:

A holder for radio vacuum tubes comprising a base member, contacts therein for engaging the prongs of a vacuum tube, a cylindrical holding element on said base in register with said contacts comprising a plurality of perforated articulate sections, at least one resilient ear on each of said sections in register with the perforations

in said sections and projecting beyond the outer surface thereof, and a clamping ring disposed around said cylindrical element above said ears and comprising a number of cam surfaces on its inner surface for engaging said sections and deflecting them inwardly when the ring is rotated in a proper direction.

WILLIAM G. LEICHNER.
